 Waddell, St. Louis, Mo.

Application August 30, 1933, Serial No. 687,466

5 Claims. (Cl. 128—25)

My present invention has relation to the provision of an apparatus for treating the eyes and more particularly relates to the provision of devices for subjecting the eyes to air pressures both above and below the normal atmospheric pressure, which changes of pressure will cause the patient to use and exercise the muscles employed in the focalization of the eye.

I am aware that it has already been suggested to provide a pair of spectacles with a pair of tubes extending from the lenses to the face about the eyes, together with a tube leading to the mouth or a compressible bulb for forcing air into or extracting it from the aforementioned tubes.

I have found, however, that in order to realize any advantage to the eyes from thus disturbing the muscular balance which any particular patient has established with respect to his or her own eyes the change of pressure is of importance only by reason of the muscular action it induces and the action should be uniform and the extent of such action readily and positively known and controlled.

I have further found that the muscles of the eye respond most readily and pleasantly to and are most efficaciously effected by changes which succeed each other with a suitable degree of rapidity so as to produce what may be described as a vibratory effect upon the muscles of the eye.

I have therefore had as my objects the provision of apparatus for changing the pressure in front of the patient's eye in which the latitude of such changes may be dependably measured and controlled and in which the abnormal pressure condition may be caused to vary or flutter at a rate which may be found desirable.

I have attained the foregoing objects by means of the structure illustrated in the accompanying drawings in which—

Fig. 1 is a front elevation of the stand upon which is mounted the pump and the pressure changing, measuring and control apparatus.

Fig. 2 is a side elevation of the structure shown in Fig. 1.

Fig. 3 is a section, to an enlarged scale, of the pump.

Fig. 4 is a top plan of the structure shown in Figs. 1 and 2.

Fig. 5 is a diagram of the relation between the pump and the control apparatus and the head piece which is associated with the eyes.

Fig. 6 is a central sectional elevation, to an enlarged scale, of one of the valves which is interposed in the tubes leading from the pump.

Fig. 7 is a central sectional elevation of one of the valves for controlling communication to the tubes of the head piece; and

Fig. 8 is a top plan view partially in section of the head piece and valves for producing the fluttering or relatively rapid alteration of the pressure.

Similar reference characters refer to similar parts throughout the respective views.

All of the apparatus, with the exception of the head piece and the tubes leading thereto, is mounted upon a rectangular table or stand 10 having a shelf 11 mounted between the legs or supports of the table or stand below the top thereof. At the rear and extending above the plane of the top I provide a back panel 12 which is for mounting and supporting the pressure gauges and such part of the control apparatus as are hereafter described as located thereon. The pump, and its driving mechanism for producing the changes of pressure, is mounted upon the shelf 11, together with an electric motor 13 for actuating the pump. As most clearly shown in Fig. 1, the pump is mounted between and supported by two perforated, flanged plates 14, the flanges whereof are secured by bolts 15 to the shelf 11. The pump itself, as most clearly shown in Fig. 3, comprises a pair of cylinders 16 disposed in parallel relation and extending between and through apertures provided in the plates 14. Surrounding the cylinders 16 and also extending between the plates 14 are spacer tubes 17 and closing the respective ends of the cylinders are cap-like cylinder heads 18.

Washers 19 are interposed between the plates 14 and the ends of the tubes 17 and the ends of the cylinder heads 18. The cylinder heads at one end of the cylinder 16 are centrally perforated and provided with packing gland screws 20 for the passage of piston rods 21 on the inner ends of which are secured pistons 22 which reciprocate in the cylinder 16. Between the cylinders 16 the plates 14 are perforated to receive collars 23 which form bearings for a guide rod 24. The piston rods 21 and guide rod 24 are secured in a cross-head 25. To the cross-head 25 is pivoted a link 26, the outer end whereof is secured by means of a bolt 27 and nut 28 operating through a slot 29 in a rocker arm 30. By sliding the bolt 27 to various positions in the slot 29 the stroke, or latitude of movement, of the pistons 22 may be controlled. The lower end of the rocker arm 30 is fixedly secured to a shaft 31 operating in a bearing 32 and to the opposite end of the shaft 31 is fixedly secured an arm 33 to which arm 33

is pivoted a link 34, the opposite end of which link 34 is pivotally secured to and eccentrically of a disk 35 rotated by the motor 13.

In each cylinder head 18 is set a valve 36 arranged to open upon an exhaustion stroke of the piston 22 and to seat upon a compression stroke of the said piston and a valve 37 oppositely arranged to seat upon an exhaustion stroke and to open upon a compression stroke of the said piston 22. In connection with each of the valves 36 are provided manually operated cocks 38 which are to be opened when it is desired to operate the machine upon pressures exceeding atmospheric pressure. The valve 38 is opened manually each time the piston 22 moves from the cylinder end near which valve 38 is mounted and closed on the reverse stroke, to avoid loss of pressure.

Mounted to the rear and upon the top of the table 10 are a pair of hollow cylinders 39 and 40, as most clearly shown in Figs. 4 and 5. As most clearly shown in diagrammatic Fig. 5 the valves 36 located in the respective cylinder heads are connected by suitable tubing with the cylinder 39, while the valves 37 associated with each of the cylinder heads are likewise connected by means of suitable tubing with the cylinder 40.

Interposed in the respective runs of tubing from each of the valves 36 and 37 to the respective cylinders 39 and 40 are manually operated valves 41, shown in enlarged sectional detail in Fig. 6. By reference to Fig. 6 it will be seen that by the manual operation of the milled head 42 the valves 41 can be adjusted to entirely cut off or reduce to any degree the communication between the valves 36 and 37 with the respective cylinders 39 and 40.

Mounted upon the back panel 12 of the table is a vacuum gauge 43 and a pressure gauge 44. The vacuum gauge 43 is connected by tubing 45 with cylinder 39 and the pressure gauge 44 is connected by tubing 46 to cylinder 40 so that the degree of vacuum or pressure existing in the respective cylinders 39 and 40 at any time is shown by these gauges. Also mounted upon the back panel 12 of the table 10 is a rheostat 47 included in the electric circuit for energizing the motor 13 by means of which rheostat the speed of the motor may be modified through a certain latitude.

As most clearly seen in diagrammatic Fig. 5, tubes 48 and 49 lead from cylinder 39 to the respective cylinders 50 and 51 of the head piece, and likewise, tubes 53 and 52 lead from the cylinder 40 to, respectively, the head piece cylinders 50 and 51.

Interposed in the tubes 48, 49, 52 and 53 are hand opened and spring closed valves 54, shown in enlarged sectional detail in Fig. 7. The valves 54 are located in a row upon the top of the table 10 in front of the valves 41 and for convenience in operation I have arranged the valves 54 in pairs, one of the pairs controlling the pressure and vacuum to the cylinder 50, while the other pair controls the pressure and vacuum to the cylinder 51 of the head piece.

The length of the stroke or action of the piston of either pressure or vacuum upon either eye may be influenced by the adjustment of the link 26 by means of the bolt 27 and nut 28. The period may be influenced by the operation of the rheostat 47 and the character of the action may be further influenced by closing or opening a desired number of the valves 41.

I further influence the character of the effect

upon the eyes of the operation of the machine by the provision of accumulators or storage tanks 55 and 56 connected with the respective cylinders 39 and 40 by tubes 57 and 58, in which tubes are interposed manually operated shut-off cocks 59. In addition to the foregoing means for effecting the character of the operation of the device I have a still further element to be hereinafter described.

The structure of the valves 41 is largely conventional, and, as will be seen by reference to Fig. 6, includes the valve proper 42a which seats at 42b and is caused to seat and open by the rotation of the valve stem 42c by means of the milled head 42. The valve 54 is likewise largely conventional, and, as will be seen by reference to Fig. 7, consists of the valve proper 54a, which is seated by means of the coil spring 54b. Extending downwardly from the top through the casing of the valve 54 is a rod 54c which is normally held out of contact with the valve proper 54a by means of the coil spring 54d extending between the valve casing and a milled head 54e mounted upon the top of the rod 54c so that this valve is normally closed and is caused to open by pressing upon the milled head 54e.

It will be seen by reference to Fig. 7 that if the port 54f is connected with the tube running to the cylinder 39 and the port 54g is connected with the tube running to the head piece the valve 54a will seat with pressure, and also, if the port 54g is connected with the tube running to the cylinder 40 and the port 54f is connected with the head piece the valve 54a will still seat with pressure. In other words, the style of valve 54 shown in Fig. 7 may be used both on the pressure and vacuum lines by merely reversing its connections.

The head piece, as most clearly shown in Fig. 8, comprises a pair of cylinders 50 and 51, each provided with a laterally projecting bar 62 and 63, the extending ends of which are provided with slots 64 through which operates a bolt with a milled headed nut 65 by means of which the separation of the cylinders 50 and 51 and their parallelism or obliquity may be easily adjusted. In the forward end of each cylinder is mounted a suitable lens 66 and on the opposite ends of the cylinders 50 and 51 are mounted cups 67 shaped to conform to the configuration of the face about the eyes. Over the rear ends of the cups 67 is mounted a compressible annulus 68 of rubber or other suitable material to substantially seal the contact with the face. Means are provided in the lower portions of the cylinders 50 and 51 for making connection with flexible extensions with the tubes 48 and 53 and 49, and 52, as clearly shown in Fig. 5. I have indicated the ports through which these tubes make connection with the reference characters 48a, 53a, 49a and 52a respectively.

In the sides of the cylinders 50 and 51 are provided ports in which are mounted valves 69 and 70, the valve 69 being held closed by a light spring 69a against the entry of any air into the cylinder, whereas the valve 70 is held closed by spring 70a against the emergence of any air from the cylinder. The outer ends of the valves 69 and 70 screw into ports in the side of a cylinder 71, in the opposite side of which cylinder 71 are valves 72 and 73 which are arranged to and do operate precisely like the valves 69 and 70 to which they are respectively opposite. One end of the cylinder 71 is permanently closed and into the opposite end screws a plug 74 which is centrally bored 75

and tapped to receive the threaded stem 75 upon the outer end of which is provided a knurled cap 76. Secured to the inner end of the stem 75 is a cylindrical plug 77 which is caused to travel backwards and forwards in the bore of the cylinder 71 by rotating the stem 75.

When pressures below atmospheric pressure are being employed upon the eye or eyes and the plug 77 is in a position between the valves 69 and 72, as shown in detail in Fig. 8, this portion of the apparatus is inactive, but should the plug 77 be screwed down so as to open up communication between the valves 69 and 72 air would enter against the action of the springs 15 which would cause a flutter of the valves upon their seats and a like fluttering alteration of the pressure within the cylinders 50 and 51 and effective upon the eyes. On the other hand, if pressures above atmospheric pressure were being employed in the cylinders 50 and 51 and a communication was open between the valves 70 and 73, as shown in detail in Fig. 8, such excess pressure would escape against the action of the springs in a fluttering manner, but if the plug 25 77 is screwed in sufficiently far to block communication between the valves 70 and 73, the structure would be rendered inoperative to cause a fluttering change of pressure.

The apparatus is operated as follows: The motor 13 is started and any or all of the valves 41 are manually opened to secure the desired degree of vacuum and pressure in the cylinders 39 and 40, as indicated by the gauges 43 and 44, it being understood that when pressure is being built up the cocks 38 are manually opened. The head piece is then fixed upon the head of the patient and the patient is directed to view a suitable target through the lenses 66. Then, in accordance with the abnormality of the patient, either myopic or hypermetropic, air is either introduced into or exhausted from one of the cylinders 50 and 51, and then the other cylinder, by the manipulation of the appropriate ones of the four valves 54. Such action usually and normally results in substantially clearing the patient's vision. The strength of the fluctuation or periodicity is then modified by the adjustment of the plug 77 in the cylinder 71. If it is desired to strengthen or increase the periodic character the accumulation tanks 55 and 56 are then closed off by the operation of the valves 59. By cutting off progressively the respective heads of the cylinders 16 by the operation of the valves 41, the periodic character is still further altered and by the adjustment of the link 26 in the slot 29 the stroke can be still further changed. The rheostat 47 also may be employed in delaying or accelerating the period. The imposition of pressure or the relief of pressure from the eyes in proper cases distinctly releases the tension of the eye muscles. In the employment of relatively long and slow changes of pressure the patient is inclined to meet the action of the machine with some conscious muscular effort. In quick changes of pressure there is little effort made to muscularly meet the changes of condition. In any of these changes the muscles of the eye are gently moved, which is

salutary to them, as like action is to all other muscles of the body, through physiological causes, and the normal physiological results are the improvements of the strength and physical condition of the muscles.

Having described my invention what I claim as new and desire to secure by Letters Patent is:

1. In combination with a head piece adapted to fit the face about the eyes providing compartments in front of the eyes through which vision may be exercised, a pressure cylinder and a vacuum cylinder, means for establishing controlled selective communication between said cylinders and said respective compartments, a pump for maintaining pressure and vacuum in said cylinders, and independent means associated directly with the compartments of the head piece for imparting a vibratory character to the pressure within the compartments of the head piece when the pressure in said compartments is either above or below atmospheric pressure.

2. In combination with a head piece adapted to fit the face about the eyes providing compartments in front of the eyes through which vision may be exercised, a pressure cylinder and a vacuum cylinder, means for establishing controlled selective communication between said cylinders and said respective compartments, a pump for maintaining pressure and vacuum in said cylinders and means for cutting out said cylinders and causing said pump to be directly effective upon the compartments of said head piece.

3. In a machine for exercising the interior muscles of the eyeballs, a head piece adapted to fit the face about the eyes providing compartments in front of the eyes through which vision may be exercised, and means for independently altering the pressure to controlled and known extents in said respective compartments whereby the eyes are induced to meet by muscular action the effects of pressure alteration.

4. In a machine for exercising the interior muscles of the eyeballs, a head piece adapted to fit the face about the eyes providing compartments in front of the eyes through which vision may be exercised, a pressure cylinder and a vacuum cylinder and means for establishing controlled selective communication between said cylinders and said respective compartments whereby the muscles of the eyes are concurrently called upon to meet the change in curvature of the eyeballs caused by the alterations of pressure.

5. In a machine for exercising the interior muscles of the eyeballs, a head piece adapted to fit the face about the eyes providing compartments in front of the eyes through which vision may be exercised, a pair of ports in each of said compartments, means associated with said ports for withdrawing air from one of said ports and introducing air through the other of said ports and independent manually operative means for controlling the passage of air to and from the respective compartments through said ports whereby abnormality in muscle action in the eyeballs may be relieved and concurrent muscular action induced in the respective eyeballs.

GARRY MIKE O'GORDEEN.
